UNITED STATES PATENT OFFICE.

GEORGE C. HUGG, OF PHILADELPHIA, PENNSYLVANIA.

VALVE FOR MUSICAL WIND-INSTRUMENTS.

SPECIFICATION forming part of Letters Patent No. 254,136, dated February 28, 1882.

Application filed October 1, 1881. (No model.)

To all whom it may concern:

Be it known that I, GEORGE C. HUGG, a citizen of the United States, residing in the city and county of Philadelphia, State of Pennsylvania, have invented a new and useful Improvement in Valves for Wind Musical Instruments, which improvement is fully set forth in the following specification and accompanying drawings, in which—

10 Figure 1 is a side elevation of the portion of a wind musical instrument having my invention applied to it. Fig. 2 is a bottom view thereof. Fig. 3 is a vertical section in line x x , Fig. 2. Fig. 4 is a vertical section in line y y , Fig. 2.

15 Similar letters of reference indicate corresponding parts in the several figures.

My invention consists of the hinges of organ-valves, of peculiar construction, whereby butt-hinges are avoided, thus obviating cutting and piercing of both the valves and reed-board for the hinges and screws thereof, and permitting the valves to form close joints with the board, and singing of said hinges is also obviated, there being, furthermore, a simplification in the construction of parts and reduction of expense thereof.

20 It also consists of a guard for preventing the jumping of the valves from their connections with the reed-board.

25 Referring to the drawings, A represents the keys of a wind musical instrument, and B the reed-board, C the valves, and D the push-pins thereof, all of which, excepting as far as relates to my invention, are of usual form.

30 The valves C are hinged to the reed-board at their sides, in contradistinction to their ends.

35 It will be seen that when the keys are operated the valves are depressed and turn downwardly on their side hinges, thus uncovering all of the reed-openings of the respective sets to the same extent. By this provision the air passes in uniform volume through the 40 openings of the set of reeds, so that there is

an equality of sound of each reed. Furthermore, when short notes are played, all of the reeds of the sets are sounded, since their openings are uncovered simultaneously and to the same extent.

50 The hinges of the valves are formed of gudgeons a on the ends of the valves and integral therewith, and eyes a' , which are secured to the reed-board or proper connecting part and receive the gudgeons a . By this construction both ends of the valves are firmly and properly supported and mounted without the employment of butt-hinges, which are liable to sing and require cutting away of the wood-work to receive the butts and piercing of the 55 same for the numerous screws employed.

Secured to the under side of the reed-board is a guard or arm, E, which extends transversely to the longitudinal direction of the valves of the instrument and horizontally 60 thereunder, said arm being separated from the reed-board a distance to limit the descent or opening of the valves beyond what is sufficient for all practical purposes common to all of the valves. By this provision the valves 65 cannot pass or jump their centers or be otherwise displaced, and thus the return of the valves to their seats, when required, is assured.

Having thus described my invention, what I claim as new, and desire to secure by Letters 70 Patent, is—

75 1. The organ-valve formed with the gudgeons a integral therewith, in combination with the eyes a' , secured to the reed-board and receiving said gudgeons, substantially as and for 80 the purpose set forth.

2. The reed-board and valves, in combination with the guard extending under all of the valves as a common check or stop, substantially as and for the purpose set forth.

GEO. C. HUGG.
